DIRECTION INDICATING DEVICE

Joseph Bell, Cincinnati, Ohio

Application August 17, 1933, Serial No. 685,602

13 Claims.

(Cl. 177—327)

My invention relates to direction indicators or signals particularly adapted for use on automobiles and the application is a continuation in part of my application for patent on Direction indicating device, filed June 21, 1929, Serial No. 372,625.

It is well known that safety and courtesy necessitate the use of some means to indicate in which direction an autoist intends driving upon reaching an intersection or other point where he intends to deviate from a straight path of travel. The most common means heretofore employed to effect this indication requires the driver to extend his arm beyond the body line of the car. This method is unsafe and hazardous to the driver of his and other cars and to pedestrians. While the driver's hand is so extended, he has but one hand with which to operate the steering wheel and other mechanism and consequently materially increases the chances of accidents or if he places both hands on the wheel, he frequently has not given sufficient warning of his intended deviation. In rainy and inclement weather it is even more inconvenient, troublesome and dangerous for the driver to extend his arm outside the car.

The principle object of my invention is to provide efficient signaling means which will permit the driver to retain both hands on the steering wheel inside the car and yet more clearly and visibly indicate to other cars and pedestrians his intended direction of travel. Not only will the device materially decrease the probability of accidents and remove the discomfort incident to extending the hand but it will also tend substantially to speed up traffic and decrease congestion.

Another object of my invention is to provide a direction indicator actuated electrically from within the car to insure facility and speed of operation.

Another object of my invention is to provide an indicator though simply and cheaply manufactured and installed yet retaining maximum efficiency.

Another object of my invention is to provide a more simple and efficient arrangement between the rotor and stator of an electro motor for limiting the arcuate movement of the rotating shaft and indicating member.

Another object of my invention is to provide an indicating and signaling device enclosed within a casing so as to have the moving parts protected from the weather and from tampering by other persons.

Another object of my invention is to provide

means for clearly and quickly indicating to the driver whether or not the intended signal is being given.

Another object of my invention is to provide means for selectively giving a constant signal in either direction or an oscillating signal rotating backwardly and forwardly in either direction.

Another object of my invention is to provide a signaling device in the same casing with a conventional stop and tail light and to provide a movable indicating member in the stop and tail light field.

I have provided the illuminated indicating member in the same casing with the stop and tail light since autoists concentrate their vision on these lights when following a vehicle. In the particular embodiment of my invention selected for illustration:

- Fig. 22 is a section on the line 22—22 of Fig. 23, Fig. 23 is a section on the line 23—23 of Fig. 18, Fig. 24 is a wiring diagram of the device, Fig. 25 is a cross sectional detail, taken on the line 25—25 of Fig. 2, Fig. 26 is a detail section, taken in the plane of the line 26—26 of Fig. 2, Fig. 27 is a detail section, taken in the plane of the line 27—27 of Fig. 2, and
- 10 Fig. 28 is a detail section, taken in the plane of the line 28—28 of Fig. 2.
- Referring now to the drawings and particularly Figs. 1-4 inclusive, my indicator is preferably housed in the casing 30 (Fig. 1) which may be of any suitable size and shape and which may be secured to any bracket or any other portion of the motor vehicle by means of screws 31. The screws 31 are provided not only to secure the casing to the motor vehicle but also to secure the yoke 32 and terminal block 33 within the casing 30. The poles 34 and 35 with the usual windings are secured to the yoke 32 by means of rivets 36 and 37 respectively. The supports 38 and 39 for the stop, tail light and indicator illuminator bulb sockets are riveted to the yoke by means of the rivets 36 and 37 which secure the stator poles 34 and 35 to the yoke. The stop light and indicator light bulb 40 seats in its socket 41 secured to the supports 38 and 39 by means of screws 42 and 43. 20 The terminal block 44 is secured to the socket 41 by means of screws 45 and 46 and the contact spring member 47 is secured to the terminal block 44 by means of contact screws 48 and 49. The tail light and indicator light bulb 50 seats in its socket 51 secured to the supports 38 and 39 by means of screws 52 and 53. The terminal block 54 is secured to the socket 51 by means of screws 55 and 56. The spring contact member 57 is secured to the terminal block 54 by means of contact screws 58 and 59. The pivot bearing 60 is adjustably secured to the yoke 32 and has its bearing point extending laterally inwardly to receive the end of the rotor shaft hereinafter described. The bearing plate 61 is secured to the yoke 32 by means of screws 62 and 63. The bushing 64 is pressed into the bearing plate 61 and is adapted to act as a bearing for the rotor shaft hereinafter described. The stator pole faces 65 and 66 are secured to the cores of the poles 34 and 35 respectively by means of rivets 67 and 68. The rotor shaft 70 rotates between the pivot bearing 60 and thru the bushing 64 extending beyond the bushing 64 outside of the yoke 32. Near its inner end the shaft 70 carries the insulated collector ring body 71 which carries the three collector rings 72, 73, and 74. The collector ring brush 75 is secured to the terminal block 33 by means of screw 36 and has three fingers 77, 78, and 79 contacting the collector rings 72, 80, and 74 respectively. The single fingered brush 80 secured to the terminal block 33 by means of screw 81 contacts the collector ring 73 when the rotor shaft is moved approximately 80° and normally it rests against the insulated collector ring body 71. The shaft 70 carries the three pole rotor 82 which rotates between the stator pole faces 65 and 66. The rotor 82 has a positive wound pole 83 and negative wound poles 84 and 85. The shaft 70 on the portion outside of the yoke 32 is notched to receive a washer 86 to retain the torsion spring 87 in proper position on the shaft. The spring supporting washer 88 has a finger bent over and extending inwardly parallel to the shaft and in such position as to be between the two ends 89 and 90 of the spring 87. The neutral

adjusting member 91 secured to the bearing plate 61 in any suitable manner has its end bent outwardly and parallel to the shaft so that the ends of the spring 87 rests against it retaining one end of the spring while the other end is flexed outwardly between rotation of the shaft and the spring supporting washer 88. A flange 92 is secured on the end of the shaft 70 so as to carry the discs and indicating members hereinafter described.

Referring now particularly to Figs. 5-16 inclusive I have provided several types of indicating and signaling members and arrows. In Figs. 5, 6, and 7 I have shown an oscillating indicating and signaling disc 100 having a translucent stop and tail light field 101 preferably of a red color. I also provide in the disc bull's eyes 102 preferably translucent and of a lighter color than the field 101 behind which are the tail light and stop light bulbs 40 and 50 when the disc is in neutral position or non-indicating position. I also provide an opaque area 103. The arrow portion 104 of the disc is preferably translucent of a contrasted color with the stop and tail light field 101. The holes 105 are provided through the disc 100 so that it may be readily secured to the flange 92 on the end of the rotor shaft 70. The casing window or lens 106 is provided with translucent portions 107 and 108 through which the stop light and tail light show and also an opaque portion 109 to outline the double arrow or transparent portion 110. When the disc 100 is rotated in either direction the portion 104 is behind the portion 110 of the lens so that an indication is given in one direction while the opaque portion 103 covers the other side of the double arrow 110. At the same time the bull's eyes 102 come behind the translucent portions 107 and 108.

Referring now particularly to Figs. 8, 9, and 10 the stationary disc 111 is rigidly secured by means of screws 62 and 63 to the bearing plate 61 so that the translucent bull's eyes 112 are directly in front of the stop and tail light. The entire disc with the exception of the bull's eyes 112 is translucent and forms the stop and tail light field, the portion being of lesser translucency than the bull's eyes. The shaft 70 extends through the disc 111 and carries on its outer end the oscillating indicating arrow 113 of highly translucent color contrasting with the color of the disc 111. The casing window 114 is of transparent material. The window frame 115 has opaque projections 116 which conceal a portion of the arrow 113 when it is in non-indicating position.

Referring now particularly to Figs. 11, 12, and 13 I provide an oscillating disc 117 having a translucent stop and tail light area 118 and with translucent bull's eyes 119 of higher translucency than the stop and tail light field. The portion 120 forming the double arrows is of higher translucency than the bull's eyes and tail light and stop light field. The casing lens 121 is provided with a field 122 of high translucency and with horizontal portions 123 which are transparent. When the disc 117 is in non-indicating position or the position shown in Fig. 12 both arrows fall mostly behind the translucent portion 122. Translucent bull's eyes 124 are provided in the lens 121 so as to be in alignment with the bull's eyes 119 when the lens 117 is in its non-indicating position. When the lens 117 is oscillated to the position shown in Fig. 13 one of the arrows falls behind the transparent portion 123 and the other arrow is behind the translucent field 122 covering the bull's eyes 124.

Referring now particularly to Figs. 14, 15, 16 I provide a stationary opaque shield 125 secured to the bearing plate 61 in the same manner as in Fig. 8. On the end of the shaft 70 is the indicating arrow having a translucent portion 126 contrasting with the opaque portion 127. On the arrow portion I provide bull's eyes 128 of higher translucency than the arrow behind which are the stop and tail light bulbs when the indicator is in neutral position. The casing lens 129 is provided with translucent portions 130 for the stop and tail light field. The transparent arrow portion 131 is provided in the opaque field 132. When the arrow is oscillated it falls behind the double arrow portion 131 of the casing lens. At the same time the opaque portion 127 of the arrow covers the other end of the transparent double arrow 131 and the rounded projections shift in front of the light bulbs preventing glare.

Referring now particularly to Figs. 17-24 inclusive I preferably provide a switch for operating the indicating mechanism of the type similar to that shown in my co-pending application, Serial No. 682,384 for Signaling device, filed July 26, 1933. The switch is so constructed that the signal may be hooked up electrically to operate either a constant signal in either direction or an oscillating signal in either direction. The casing 140 is provided to receive the movable member 141 and the stationary member 142, the casing being adapted to be attached within the motor vehicle at any convenient or desired point. The movable member 141 carries a manually operated lever 143 and has socketed therein the telltale light bulb 144 and positive spring contact member 145 contacting with the base of the bulb 144. The bulb 144 is grounded through the screw 146 which secures the lever 143 to the movable member. The negative spring contact member 147 is also secured to the movable member near its lower portion. The stationary member 148 is provided with positive contacted post 149 and negative contact post 150, field posts 151 and 152, rotor post 153 and oscillating terminal post 154, actuating member 155, contact tongue 156, strap 157 and strap 158. Between the spring contact tongue 156 and the actuating member 155 is placed an insulating strip 159. The actuating member 155 is rigidly secured at both its ends against longitudinal movement by means of clamping screws 160 and 161 and is of reduced cross-section so as to be readily subject to expansion from heat caused by current coming through the main feed line, the actuating member being part of the main electrical circuit.

If it is desired to have the signal remain in a fixed position for indication and not to oscillate back and forth after the lever 143 has been turned to the right or left, a lead wire is connected from the battery to the positive contact post 149. With this hook up the member causing the oscillation, that is the actuating member 155 is by-passed and continuous non-interrupted current flows from the battery to the signal operating mechanism as long as the switch lever is in a right or left hand position. When it is desired to have the indicating member oscillate back and forth from a neutral to either a right or left hand position a lead wire is connected from the battery to the positive contact post 154. Current then flows through the spring contact tongue 156 which normally tends to spring away from contact with post 154, to the strap 157 into the actuating member 155, to the strap 158, through the positive contact spring 145, contact post 149,

contact 152 or 151 and thence to the stationary member of the indicator operating mechanism.

The operation of the device is as follows: First if it is desired to give a constant or non-oscillating indication the positive feed line from the battery is connected to the contact post 149. The negative feed line is connected from the battery to the negative contact post 150. If a left hand turn is to be indicated the lever 143 is manually moved to the left and the spring contact member 145 then contacts the posts 149 and 152. At the same time spring contact member 147 contacts the posts 150 and 151. Current then flows from the battery through the contact post 149, spring contact member 145, contact post 152 to the stationary member of the indicator mechanism, to post 151, to spring 147, to negative post 150 and thence to the negative post of the battery thus energizing the stationary member of the indicator mechanism. At the same time the switch is in its left hand position current flows through the spring contact member 145 to the contact post 153, through the line 162, the three fingered brush 75, collector rings 72, 73 and 74, through collector ring 73 to the positive rotor pole windings 83, from collector rings 72 and 74 to the negative rotor pole windings 84 and 85 respectively, through the ground 163 thus energizing the rotor poles. Both circuits are now closed, the rotor will move in left hand rotation approximately 45°, then the collector ring 72 which does not go entirely around the circumference of the member of the collector ring body 71 breaks contact with the brush finger 77 and as the current through rotor pole winding 85 is interrupted the pole 85 will become neutral as it passes about the center line of the pole of the stationary member 34. The rotor is then magnetically unbalanced but will continue to rotate until the projection 164 strikes the abutment 165 on the stator 66 and will remain in this position as long as the lever 143 is maintained in the left hand position. The indicating member will then point to the left giving an indication of an intended left hand turn. At the same time current flows through the collector ring 72 into the single fingered brush 80, contact post 81 and into the stop light 40, illuminating the indicating member (see particularly Fig. 24). As current is flowing through the switch to provide the left hand indication which also flows through the contact member 145 into the telltale bulb 144 indicating to the driver that his indicator is operating. After the signal has been given and the turn made, the lever 143 is returned to its neutral or off position and current from the battery to the switch and indicator is cut off. The torsion spring 87 then returns the rotor and shaft to its neutral or non-indicating position.

If a similar right hand signal is to be given the lever 143 is moved to the right. The spring contact member 145 then contacts the posts 149 and 151 and at the same time the spring contact member 147 contacts the posts 152 and 150. Current then flows into the stationary member of the indicating mechanism in a manner similar to that described in the left hand indication but in a reversed direction. At the same time current flows through the rotor poles in a manner similar to that described in the left hand indication. The rotor will move in right hand rotation approximately 45°, then the collector ring 74 which does not go entirely around the circumference of the member of the collector ring body 71 breaks contact with the brush finger 79 and 75

as the current through pole winding 84 is interrupted the rotor pole 84 will become neutral as it passes about the center line of the pole of the stationary member 35. The rotor is then magnetically unbalanced but will continue to rotate until the projection 164 strikes the abutment 166 on the stator 65 and will remain in this position as long as the lever 143 is maintained in the right hand position. Current will at the same time flow into the bulb 40 as in the previous left hand indication. Current will also flow into the telltale bulb in a like manner as in the left hand indication. Normally the single fingered brush 80 is out of contact with the collector ring 73 when the mechanism is in a non-indicating position and consequently current can flow from the stop light switch into the stop light without passing through the indicator operating mechanism.

If it is desired to give an oscillating indication rotating back and forth of the indicating member the positive wire from the battery is connected to the contact post 154 and the negative wire from the battery is connected to the contact 150 as in the previous operations just described. Current will then flow through the spring contact tongue 156 and actuating member 155 through strap 158, to post 149 and in a similar manner to the indicator operating mechanism. As current flows through the actuating member 155 it becomes heated and bulges outwardly since it is secured longitudinally at both its ends and allows the spring contact tongue to break contact with post 154 for an instant. In a very short while the actuating member becomes cooled and contracts back into its normal position closing the circuit by again pressing tongue 156 against post 154. This expansion and contraction continues as long as the lever 143 remains in the right hand position. This expansion and contraction will continue to make and break the circuit as long as the lever 143 is maintained in either a right or left hand position causing the indicating member to oscillate back and forth and at the same time flicker the telltale bulb simultaneously with the movement of the indicating member. The cycle of oscillating may be varied by changing the cross-sectional area of the actuating member 155 and the tension of contact tongue 156 and the adjustment of post 154.

It can readily be seen that the electromotor or operating mechanism for the signal together with the signaling member is entirely enclosed and protected within the casing.

If a constant signal is being given by the indicating member the telltale bulb remains constantly lighted as long as this signal is being given. If an oscillating signal is being given by the indicator member the telltale bulb if the indicator is properly functioning will flicker on and off simultaneously with the oscillations of the indicating member. At the same time the stop light and indicator illuminating bulb will also flicker on and off with the oscillations of the indicating member. If when such a signal is being given the telltale bulb remains constantly lighted it indicates to the driver that the actuating member 155 is not expanding and breaking contact momentarily due to the fact that insufficient current is passing through the line possibly due to burning out of the illuminating bulb or some other defect in the mechanism. In such a case sufficient current may pass through the line to actuate the rotor and the signaling member but not to illuminate the signal and the signal will be constant instead of oscillating. Naturally such

difficulty will be immediately noticed by the vehicle operator.

It can also readily be seen that no additional light for illuminating the indicating member is necessary since the conventional stop light is utilized for this purpose as is also the tail light.

While the actuating member 155 has been shown within the switch casing, it may be placed in any other convenient location.

While the invention has been described above in its preferred form, it will be obvious that various changes and modifications can be made therein without departing from the spirit or scope thereof and it is therefore desired that only such limitations be imposed thereon as are necessitated by the prior art or specifically set forth in the claims.

Having thus described my invention what I claim as new is:

1. A direction indicator having in combination an electromotor, a pair of stators spaced substantially 180 degrees apart in said electromotor, an armature in said electromotor between said stators, a shaft for said armature, a pair of negative coils and a positive coil on said armature spaced at equal angles to each other with the bases of the triangle formed by the coils lying between said shaft and the periphery of the armature, an indicating member secured to said shaft in a non-indicating position, means for energizing said armature, means for energizing said stators, means for de-energizing one of said coils, and coacting means on said stators and said armature limiting the arcuate travel of said indicating member from a non-indicating position to an indicating position in either direction.

2. A direction indicator having in combination an electromotor, a stator in said electromotor, said stator comprising a pair of cores of magnetic material spaced substantially 180 degrees apart and having an energizing coil surrounding each core, an armature in said electromotor between the cores of said stator, a shaft for said armature, a pair of negative coils and a positive coil on said armature spaced at equal angles to each other with the bases of the triangle formed by the coils lying between said shaft and the periphery of the armature, an indicating member secured to said shaft in a non-indicating position, means for energizing said stator, means for energizing and actuating said armature and means for limiting the arcuate travel of said indicating member from a non-indicating position to an indicating position in either direction.

3. A direction indicator having in combination an electromotor, a stator in said electromotor, said stator comprising a pair of cores of magnetic material spaced substantially 180 degrees apart and having an energizing coil surrounding each core, an armature in said electromotor between the cores of said stator, a shaft for said armature, a pair of negative coils and a positive coil on said armature spaced at equal angles to each other with the bases of the triangle formed by the coils lying between said shaft and the periphery of the armature, an indicating member secured to said shaft in a non-indicating position, means for energizing said stator, means for energizing and actuating said armature and fixed non-resilient abutments on said stator and a fixed non-resilient projection on said armature limiting the arcuate travel of said armature to an indicating position.

4. A direction indicator having in combination an electromotor, a stator comprising a pair of

cores spaced substantially 180 degrees apart in said electromotor, a magnetically unbalanced armature in said electromotor comprising a pair of negative poles and a positive pole spaced at 5 equal angles to each other, a shaft for said armature, an indicating member secured to said armature shaft in a non-indicating position, means for energizing said stator, means for energizing and actuating said armature and coacting means between said armature and said stator for limiting the arcuate travel of said armature and indicating member to an indicating position on either side of said non-indicating position.

5. A direction indicator having in combination 15 an electromotor, a stator comprising a pair of cores spaced substantially 180 degrees apart in said electromotor, a magnetically unbalanced armature having a pair of poles wound for one polarity and another pole wound for opposite polarity in said electromotor, said poles being spaced at equal angles to each other, a shaft for said armature, an indicating member secured to said armature shaft in a non-indicating position, means for energizing said stator, means for energizing and actuating said armature and coacting means between said armature and stator for limiting the arcuate travel of said armature and indicating member to an indicating position on either side of said non-indicating position.

30 6. A direction indicator having in combination an electromotor, a stator comprising a pair of cores spaced 180 degrees apart in said electromotor, an armature in said electromotor between the cores of said stator, a shaft for said armature, an indicating member secured to said armature shaft in a non-indicating position, means for energizing said stator comprising consequent wound poles on said stator, electrical means for causing an interrupted current to pass to the armature 35 for oscillating said armature, means normally maintaining said armature in neutral position and for returning said armature to neutral position after it has been oscillated and means for limiting to a pre-determined degree the oscillation of said armature in either direction.

40 7. A direction indicator having in combination an electromotor, an armature in said electromotor, a shaft for said armature, said armature adjacent to its outer periphery carrying a plurality 45 of equally spaced energizing coils consisting of a pair of coils of one polarity and another coil of opposite polarity, a stator in said electromotor comprising a pair of cores disposed on opposite sides of said armature, an indicating member secured to said armature shaft in a non-indicating position, means for energizing said stator, means 50 for energizing and actuating said armature, coacting means between said armature and stator for limiting the arcuate travel of said armature and means separate and apart from said indicator for either oscillating said indicator or causing said indicator to rotate one-fourth from a non-indicating position.

65 8. A direction indicator having in combination an electromotor, an armature in said electromotor, said armature adjacent to its outer periphery carrying a plurality of equally spaced energizing coils consisting of a pair of coils of one polarity and another coil of opposite polarity, a 70 stator in said electromotor comprising a pair of cores positioned on opposite sides of said armature, a shaft for said armature, an indicating member secured to said armature shaft in a normal non-indicating position, means for energizing said stator, means for energizing and actuating

ing said armature, coacting means between said stator and said armature to limit the arcuate travel of said indicator one-fourth revolution in either direction, and selective means for either oscillating said indicator or causing said indicator to move to an indicating position.

9. In a three position traffic signal device, a motor including a shaft, bearings for said shaft, an armature of magnetic material mounted on said shaft with its outer surface divided into a plurality of equally spaced pole portions concentric with said shaft, portions of reduced cross-section between said pole pieces and energizing windings about said pole portions between said shaft and the outer periphery of said armature, a stator 15 member of magnetic material including a pole piece on each side of said armature and at right angles to said shaft and having inner surfaces substantially equally spaced from the outer surfaces of said armature, a three position indicating member, means connecting said shaft and indicator in such relation that the indicator is in a non-indicating position when the motor is de-energized, and stop means for stopping said indicator in a position on each side of said non-indicating position and at an angle thereto.

10. A direction indicator having in combination an electromotor, a stator in said electromotor comprising a pair of consequent wound poles spaced substantially 180 degrees apart, an armature between said poles, equally spaced apart, energizing coils on said armature comprising a pair of negative coils and a positive coil, a shaft for said armature, an indicating member secured to said armature shaft in a non-indicating position, 30 means for energizing said stator and armature for actuating said armature in either direction and means for stopping said indicating member in a position on each side of said non-indicating position and at an angle thereto.

40 11. A direction indicator having in combination an electromotor, a stator in said electromotor comprising a pair of consequent wound poles, an armature between said poles spaced substantially 180 degrees apart, equally spaced apart energizing coils on said armature comprising a pair of negative coils and a positive coil, a shaft for said armature, an indicating member secured to said armature shaft in a non-indicating position, 45 means for energizing said stator and armature for actuating said armature in either direction, and abutments on said stator and a projection on said armature limiting the arcuate travel of said armature and indicating member to an indicating position on either side of said non-indicating 50 position.

55 12. A direction indicator having in combination an electromotor, an electrical circuit for said motor, a stator in said electromotor comprising a pair of consequent wound poles, an armature between said poles spaced substantially 180 degrees apart, an uneven number of energizing coils of opposite polarity equally spaced apart on said armature, means for breaking the circuit to one of said armature coils while passing through the center line of the opposite polarity stator pole, a shaft for said armature, an indicating member secured to said armature shaft in a non-indicating position, means for energizing said stator and actuating said armature in either direction to an indicating position and means for stopping said armature in either indicating position.

60 13. A direction indicator having in combination an electromotor, an electrical circuit for said motor, a stator in said electromotor comprising a 70

pair of consequent wound poles, positioned 180 degrees apart, an armature between said poles, an uneven number of energizing coils of opposite polarity equally spaced on said armature, means for breaking the energizing circuit to one of said coils while said coil passes a stator pole of opposite polarity, a shaft for said armature, an indicating member secured to said armature shaft in

a non-indicating position, means for energizing said stator and actuating said armature in either direction to an indicating position and abutments on said stator and a projection on said armature limiting the arcuate travel of said armature and indicating member to either indicating position. 5
